DETERGENT BREAKER COMPOSITION

James Stuart Frank, 7057 N. Fairchild Circle,
Milwaukee, Wis. 53217

No Drawing. Filed Sept. 20, 1965, Ser. No. 488,813
5 Claims. (Cl. 252—358)

This application is a continuation-in-part of Ser. No. 321,676 filed November 6, 1963, now abandoned.

This invention relates to the degradation of synthetic detergents, and particularly to the treatment of waters containing synthetic detergents so as to inhibit foaming and to cause the breakdown of the synthetic detergent molecules.

One of the problems in present day water supplies is that foam appears on the rivers or in the drinking water because the synthetic detergents now used do not decompose under conventional disposal or sewage treatment. Previously known materials or compounds have not satisfactorily solved the problem of effectively inhibiting foam and of breaking down the synthetic detergent molecule remaining in the waste water. Such a degradation material must be inexpensive, non-poisonous and effective. Synthetic detergents of anionic, cationic and nonionic categories have come into quite general use. The detergent molecule has a dual character in that part of the molecule has water attracting or hydrophilic tendencies, while the other part has hydrophobic properties. It is because of this peculiar molecular structure that detergent solutions possess good wetting and emulsifying power, that they foam and are adapted to clean soiled surfaces. The generic formula of anionic aliphatic sulfonates can be written $R(OSO_3-Na^+)$ in which R contains one or more hydrophobic groups. One example is sodium dodecyl benzene sulfonate. These are the alkyl benzene sulfonates commonly termed "ABS."

The cationic surface active agents, like the anionic agents, have hydrophilic and hydrophobic groups, ionization occurring in the cation. Examples of this class are the salts of strong quaternary bases. The nonionic surface active agents are ones wherein an adequate degree of hydration can be achieved if a sufficient number of non-ionizing polar groups are present. An example of such are the polyethoxy agents having the general formula $R(CH_2CH_2O)_mH_n$.

One of the objects of the invention is to provide a synthetic detergent degradation compound which will efficiently break down the synthetic detergent molecule in aqueous solution without contaminating the liquid to be separated from the synthetic detergent.

Another object of the invention is to provide a compound which can be applied in diluted form or directly to the waters to be treated.

The above and other objects of the invention can be accomplished by the provision of a semisoluble complex synthetic detergent breaker composition comprising 2 to 60% by weight, dialkylpolysiloxane having the general formula $(RSiO)_n$ with R alkyl radicals at the chain ends, where the alkyl is selected from the group consisting of methyl, ethyl, propyl, up to 6 carbon atoms, and where n is an integer representing the degree of polymerization or association and n may range, for example, from 2 to 100 or more; 2 to 70%, by weight, alkyl-siloxymetallic complex where the complex chain (organo-silicon) has the general formula $(RSiO)_3M$ where M is the metallic ion selected from the group consisting of aluminum, ferrous, ferric, cobalt, etc., and R is an alkyl selected from

2

the group methyl, ethyl, propyl, up to 6 carbon atoms; 10 to 70%, by weight, metallic sulfate where the metallic ion is selected from the group of aluminum, ferrous, ferric, cobalt, etc. (and usually corresponds to the metal in 5 the alkylsiloxymetallic complex); 0.5 to 20%, by weight, silica gel as a common base; and 0.2 to 5.0%, by weight, sulfuric acid or other sulfurous acid or ascorbic acid to control the pH. In the case of dialkylpolysiloxane, generally preferred are the relatively high molecular weight polymers wherein n may be, for instance, 30 to 50.

One dialkylpolysiloxane which can be used is dimethylpolysiloxane, such being prepared by adding dimethyl-dichlorosilane to water (demineralized) which yields dimethylsilanol. The dimethylsilanol upon standing will decompose to dimethylpolysiloxane and hydrogen chloride gas, with just the dimethylpolysiloxane remaining in the reacting vessel. Another dialkylpolysiloxane that can be used is diethylchlorosilane instead of dimethyl-dichlorosilane, such yielding diethylsilanol and diethylpolysiloxane.

An example of a trialkylsiloxymetallic complex is triethylsiloxyaluminum formed by adding powdered aluminum to triethylsilanol which upon the application of heat yields triethylsiloxyaluminum plus hydrogen gas. Sulfuric acid is then added in a small quantity to keep the pH down.

A further example of a trialkylsiloxymetallic complex is trimethylsiloxyaluminum formed by reacting trimethylsilanol with powdered aluminum, yielding the desired trimethylsiloxyaluminum. Again sulfuric acid is added in small quantity to control pH.

Example I

A synthetic detergent breaker composition was formed 35 from 40%, by weight, aluminum sulfate added to 30%, by weight, dimethylpolysiloxane. After thorough mixing, 20%, by weight, triethylsiloxyaluminum was added along with 1.5%, by weight, sulfuric acid. Then 8.5%, by weight, silica gel was added.

Example II

To 20%, by weight, dimethylpolysiloxane 50%, by weight, aluminum sulfate was added. After complete mixing, 25%, by weight, triethylsiloxyaluminum was 45 added. A trace (less than 0.3%), of sulfuric acid was added, followed immediately by the addition of silica gel, 5% by weight.

Example III

To 25%, by weight, dimethylpolysiloxane, there was 50 added 50%, by weight, aluminum sulfate. After complete mixing, 15%, by weight, trimethylsiloxyaluminum was added, followed by 2%, by weight, sulfuric acid and silica gel, 8% by weight.

Example IV

To 18%, by weight, diethylpolysiloxane, 42%, by weight, aluminum sulfate was added and completely mixed. Then 31%, by weight, triethylsiloxyaluminum was added, followed by 9%, by weight, silica gel and a trace of sulfuric acid.

The dialkylpolysiloxanes mentioned were found to have excellent defoaming characteristics, the defoaming apparently being a surface effect without chemical reaction between the polysiloxanes and the alkyl benzene sulfonates. The alkylsiloxymetallic complex as described was

found to be, along with a metallic sulfate, an efficient coagulant but without good defoaming characteristics.

Following is an example of test results using the synthetic detergent breaker of Example I of the invention:

Concentration ABS, p.p.m.	Time in minutes	
	75% Breaker	90% Breaker
150.....	0	0
70.....	5	4
50.....	10	7
30.....	17	14
15.....	30	
10.....		

Preferably the pH controlling substance should be added in sufficient quantity to bring the pH between 4.5 and 5.5 although the breaker remained effective to pH 7.1 where hydrolysis became a major problem.

It should be apparent that variations may be made without departing from the spirit of the invention, except as defined in the appended claims.

What is claimed is:

1. A synthetic detergent breaker composition consisting essentially of 2 to 60% by weight dialkylpolysiloxane having the general formula $(RSiO)_n$ where n is a positive integer of 2 to 100 and, where the R radicals are alkyl and at the chain ends, the alkyl radicals being selected from the group consisting of methyl, ethyl, propyl, butyl, pentyl and hexyl; 2 to 70% by weight alkylsiloxy-metallic complex having the general formula $(RSiO)_3M$ where M is the metallic ion selected from the group consisting of aluminum, ferrous, ferric and cobalt and the R radicals are alkyl selected from the group consisting of methyl, ethyl, propyl, butyl, pentyl and hexyl; 10 to 70% by weight metallic sulfate where the metallic ion thereof is selected from the group consisting of aluminum, ferrous, ferric, and cobalt; 0.5% to 20% by weight silica

gel; and 0.2 to 0.5% by weight of pH controlling material where the pH controlling material is selected from the group consisting of sulfuric acid, sulfurous acid and ascorbic acid.

5 2. A synthetic detergent breaker composition as in claim 1 consisting of 30% by weight dimethylpolysiloxane; 20% by weight triethylsiloxyaluminum complex; 40% by weight aluminum sulfate; 8.5% by weight silica gel; and 1.5% by weight sulfuric acid.

3. A synthetic detergent breaker composition as in claim 1 consisting of 20% by weight dimethylpolysiloxane; 20% by weight triethylsiloxyaluminum complex; 50% by weight aluminum sulfate; 5% by weight silica gel; and 0.2 to 0.3% by weight sulfuric acid.

10 15 4. A synthetic detergent breaker composition as in claim 1 consisting of 25% by weight dimethylpolysiloxane; 15% by weight trimethylsiloxyaluminum complex; 50% by weight aluminum sulfate; 8% by weight silica gel; and 2% by weight of sulfuric acid.

5 5. A synthetic detergent breaker composition as in claim 1 consisting of 18% by weight dimethylpolysiloxane; 31% by weight triethylsiloxyaluminum complex; 42% by weight aluminum sulfate; 9% by weight silica gel; and .2 to 5% of sulfuric acid.
